UNITED STATES PATENT OFFICE.

PETE HERNTON, OF HULBERT, ARKANSAS.

CATTLE GUARD.

Application filed January 28, 1926. Serial No. 84,362.

My present invention pertains to cattle guards for railways, and contemplates the provision of a guard which is simple and inexpensive in construction, adapted to be quickly and easily installed, and efficient in preventing the passage of live stock and this without liability of any stock becoming entangled with the guard and injured.

Other objects and practical advantages of the invention will be fully understood from the following description and claims when the same are read in connection with the drawings, accompanying and forming part of this specification, in which:—

15 Figure 1 is a top plan view illustration of the cattle guard constituting the best practical embodiment of my invention of which I am cognizant.

20 Figure 2 is a side elevation of the same. Similar numerals of reference designate corresponding parts in all of the views of the drawings.

25 The railway portion illustrated is of conventional construction in that it has sleepers or ties 1, and rails 2, certain of the sleepers or ties being beveled as designated by 3, and shown in Figure 2. At this point I would have it understood that it is within the purview of my invention to employ 30 comparatively wide transverse members, preferably in the form of sleepers or ties 3 with bevels of such inclination that the 35 inclination or slope of my novel guard may constitute a rise of approximately sixteen inches in five feet, this in order that the 40 guard may have a twenty-six and two thirds per cent grade with a view to increasing the efficiency thereof.

As illustrated my novel guard comprises 45 an intermediate section 4 and outer or side sections 5, the said sections being, by preference, of galvanized sheet steel. Each of the sections 4 and 5 is of general obtuse angle form in the direction of the length 50 of the railway, and the transversely coincident apices of the sections are arranged flush or substantially flush with the treads of the rails as appears in Figure 2, this relative arrangement being materially advantageous inasmuch as it conduces to the efficiency of the guard as a whole. The several sections are provided with end flanges 6, and the said end flanges 6 are designed to be connected to the beveled ties through the 55 medium of lag screws 7 or other appropriate connecting devices. It will also be

gathered from the drawings that the apex portions of the sections 4 and 5 are recessed at 8 and 9, respectively, so as to afford ample clearance for the flanges of wheels 60 moving on the rails 2.

The end portions of the sections 4 and 5 are recessed as designated by 10 and 11 so that each section is of reduced width at its ends and so that the ends of the sections will rest at opposite sides of and will not interfere in any measure with the bases 65 of the rails.

In addition to the sections 4 and 5 and the fastening devices 7, my improved guard 70 comprises longitudinal body bars 12, the said body bars 12 being of steel or other appropriate material and being arranged under the side sections 5 and superposed on the sleepers or ties below the side sections 75 5 and provided with end portions 13, angularly disposed and interposed between the flanges 6 and the beveled surfaces of the sleepers or ties 3 so as to be strongly fastened in position by the same lag screws 80 that connect the sections 5.

The body bars 12 are connected directly to the sleepers or ties below them through the medium of lag screws 14 or other appropriate means, and the inner longitudinal 85 edges of the body bars 12 serve to brace the guard structure considered as a unit against the rails so that lateral movement 90 of the guard relative to the railway is practically precluded.

90 My novel guard has been successfully used in a practical manner, and the said use has demonstrated the fact that the guard may be depended-upon to prevent the passage of horses, mules, cows and hogs; also, that 95 while the guard is adapted to serve efficiently in preventing the passage of live stock there is no liability of live stock being caught and injured by the guard, nor is there any material liability of vegetation developing and interfering with the efficiency of the guard, this because of the practically imperforate character of the guard whereby all of the 100 portion of the ground immediately under the guard is effectively shaded.

105 In addition to the practical advantages ascribed to my improvement, it will be noted that the guard is adapted to be quickly and easily installed without the employment of skilled labor, that the guard is light in 110 weight, and that by reason of the general configuration of the guard a large number

of the same may be placed in a space of small compass for storage or shipment.

I have specifically described the preferred embodiment of my invention in order to impart a full, clear and exact understanding of the said embodiment in all of its details. I do not desire, however, to be understood as restricting myself to the structure and relative arrangement of the parts as disclosed, my invention being defined by my appended claims within the scope of which structural changes and changes in arrangement may be made without departure from my invention.

Having described my invention, what I claim and desire to secure by Letters-Patent, is:—

1. A cattle guard comprising an intermediate section and side sections, each section of obtuse angle form in the direction of its length and each having end portions of reduced width to clear the bases of rails and the intermediate section having the side edges of its apex portion recessed to afford wheel flange clearances and each side section having the inner edge of its apex portion recessed for the same purpose, the apices of the sections being arranged substantially flush with the treads of railway rails, transverse members extending below railway rails and to which the intermediate and side sections are connected, and body bars arranged under the side sections and superposed on and connected to sleepers or ties below said side sections and having end portions interposed between the ends of the side sections and the said transverse members; the said transverse members being in the form of sleepers or ties with inclined upper sides.
2. A cattle guard comprising an intermediate section and side sections, each section of obtuse angle form in the direction of its length and each having end portions of reduced width to clear the bases of rails and the intermediate section having the side edges of its apex portion recessed to afford wheel flange clearances and each side section having the inner edge of its apex portion recessed for the same purpose, the apices of the sections being arranged substantially flush with the treads of railway rails, transverse members extending below railway rails and to which the intermediate and side sections are connected, and body bars arranged under the side sections and superposed on and connected to sleepers or ties below said side sections and having end portions interposed between the ends of the side sections and the said transverse members.

2. A cattle guard comprising an intermediate section and side sections, each section of obtuse angle form in the direction of its

length and each having end portions of reduced width to clear the bases of rails and the intermediate section having the side edges of its apex portion recessed to afford wheel flange clearances and each side section having the inner edge of its apex portion recessed for the same purpose, the apices of the sections being arranged substantially flush with the treads of railway rails, transverse members extending below railway rails and to which the intermediate and side sections are connected, and body bars arranged under the side sections and superposed on and connected to sleepers or ties below said side sections and having end portions interposed between the ends of the side sections and the said transverse members; the said transverse members being in the form of sleepers or ties with inclined upper sides.

3. A cattle guard for railways, comprising an intermediate sheet metal section of obtuse angle form in the direction of its length and having its apex substantially flush with the treads of the rails, side sections of obtuse angle form in the direction of their lengths arranged at the outer sides of the rails and with apices coincident with the apex of the intermediate section, and means extending under the rails and to which the end portions of the several sections are fixedly connected; the apex portions of the several sections being recessed to afford clearances for wheels, and the end portions of the several sections being reduced in width to rest at opposite sides of and against the edges of the rail bases.

In testimony whereof I affix my signature.

PETE HERNTON.
